United States Patent Office

Des. 180,318
Patented May 21, 1957

180,318

LIPSTICK CONTAINER

Philip Cortney, New York, N. Y.

Application November 6, 1956, Serial No. 43,676

Term of patent 14 years

(Cl. D86—10)

Fig. 1.

Fig. 2.

Fig. 3.

Fig. 1 is an elevational view of one side of a lipstick container showing my new design;

Fig. 2 is an elevational view of the other side; and

Fig. 3 is a top plan view, the opposite end being substantially similar thereto.

I claim:

The ornamental design for a lipstick container, substantially as shown and described.
